UNITED STATES PATENT OFFICE.

FREDERICK W. SCHENK, OF NEW YORK, N. Y.

DESIGN FOR A CLOCK FRAME.

Application filed April 6, 1928. Serial No. 26,159. Term of patent 3½ years.

To all whom it may concern:

Be it known that I, FREDERICK W. SCHENK, a citizen of the United States, whose post-office address is 655 Fifth Avenue, New York city, county of New York, and State of New York, have invented a new, original, and ornamental Design for Clock Frames, of which the following is a specification, reference being had to the accompanying drawing, forming part thereof.

Figure 1 is a front view of a clock frame showing my novel design; and

Fig. 2 is a side view thereof.

The broken lines on the front of the illustration of the clock frame in the drawing are intended to indicate that the strips of embellishment, fragments of which are shown in the upper left-hand portion of the drawing, are continued about the face of the clock frame in the space between the broken lines.

I claim:

The ornamental design for a clock frame as shown and described.

FREDERICK W. SCHENK.
